UNITED STATES PATENT OFFICE.

WILLIAM B. THAYER, OF KANSAS CITY, MISSOURI.

FLOOR-POLISHER.

1,141,287.

Specification of Letters Patent. Patented June 1, 1915.

Application filed January 13, 1914, Serial No. 811,832. Renewed March 5, 1915. Serial No. 12,412.

To all whom it may concern:

Be it known that I, WILLIAM B. THAYER, a citizen of the United States, residing at Kansas City, in the county of Jackson and State of Missouri, have invented certain new and useful Improvements in Floor-Polishers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a floor polishing machine, and has for its principal object to provide a power driven machine for polishing or grinding a board, stone, or other floor, or horizontal surface.

In accomplishing this object, I have provided improved details of structure the preferred form of which is illustrated in the accompanying drawings, wherein:

Figure I is a perspective view of a floor polishing machine constructed in accordance with my invention. Fig. II is an inverted perspective view of the polisher head, showing a number of grinding members mounted thereon. Fig. III is a vertical section of a portion of the polisher head shaft, showing its mounting and adjusting mechanism. Fig. IV is a detail perspective of the handle mounting. Fig. V is a similar view of the handle head, showing a wiring arrangement.

Referring more in detail to the parts: 1 designates a carrying member comprising a body 2, which is preferably composed of cast metal, in order to provide sufficient weight to hold the machine against vibration when the parts are in operation, and which is supported on casters 3 that are preferably provided with anti-friction bearings (not shown), in order that the body 45 may be turned freely to project the polisher head to any desired position.

The front end of the body 2 is concaved and provided with a base socket 4 into which the lower end of a carrying head 5 is projected, so that the head may be braced against transverse strain, and mounted on the head 5 is a bracket 6 having forwardly directed arms 7 provided with the spaced collars 8, within which the vertical polisher shaft 9 is revolvably and slidably mounted.

Revolvably mounted on the shaft 9 and

seated on the lower collar 8 is a bevel gear wheel 11 having a key 12 projected into a feather groove 13 in the shaft 9, so that the shaft may be revolved from the gear wheel 11 without interfering with its vertical sliding travel, and meshing with the gear wheel 12 is a bevel gear wheel 14 that is fixed on the end of the drive shaft 15, which is journaled in a bearing 16 on the bracket 6 and has operative connection with a motor 17 that is supported on the carrier body 2.

The motor is preferably of an electrical type, and has feed wires 19 that are preferably extended through a hollow handle 20, which is preferably connected with the carrying body by a yoke 21, having end members 22 lying flat against the sides of the carrier body, and provided with slots 23 through which bolts 24 on said body are projected to adjustably fix the handle thereto.

The free end of the handle body is provided with a yoke 26 that carries the grip members 27 and incloses a switch box 28, where connection is made between the feed wires 19 and fixture wires 29, and wherein the flow of current may be controlled between the separate sets of wires by means of a switch 30.

Mounted on the lower end of the shaft 9 is a head 32, preferably of cast metal, in order to provide weight or pressure for the polishers, and removably connected with the head, preferably by attaching the same thereto by lag bolts 33 are polishers 34, one form of which comprises a bracket 35 having a base adapted to lie flat against the under face of the head and receive the lag bolts 33, and having grooves 36 in its opposite face for receiving the rails 37 of a polishing or grinding member 38; the particular type of member here illustrated consisting of an emery stone, which is particularly adaptable for removing high points in a wood or stone floor.

The grooves 36 open through one end of the bracket 35, but are closed at the opposite end by a rail 39, so that a socket is formed in the face of the bracket into which the stones 105 face of the bracket into which the stones or polishers may be slid.

In actual use, I prefer to glue or otherwise seal the polishing members in their brackets, for the reason that if allowed any play therein the vibration and jar of the stones against the brackets would soon disintegrate the stones. I also preferably

mount the brackets on the under face of the carrying head, as illustrated in the drawings, for the reason that with this arrangement I not only provide for variation in the 5 grain and area of extent of initial contact, but provide an open end channel therebetween, through which material removed from the floor and from the stones may be ejected to obviate clogging of the machine.

10 While the head 32 and the polishers provide sufficient weight, the weight may, in some instances, be greater than is advisable to employ and in order to relieve the polisher of the undesirable weight, and also 15 provide for lifting the head when the machine is being moved, I mount a lifting knob 41 on the top of the shaft by dropping a flange 42 from the bottom of the knob around the shaft and projecting pins 43 20 through the flange into an annular groove 44 in the upper end of the shaft, so that when the knob is lifted the shaft may be raised without interfering with its revolute travel. The pins may be projected 25 through apertures in the knob flange and then welded or otherwise permanently secured to the flange, and the parts of the pins that project into the shaft grooves are preferably provided with anti-friction rollers 46 30 to obviate friction on the shaft when it is raised while revolving.

In order to hold the polishing head off of the floor while the machine is being moved, I pivot a post 47 on the upper bracket collar 35 8 so that it may lie flat on the collar to allow the shaft to descend to operative position, or may be raised to engage the under side of the knob when the shaft is elevated and support the knob and shaft, so that the polisher 40 head is held above the floor.

In using the machine, presuming the parts to be constructed and assembled as described, and presuming its use on a marble or like floor, the motor is connected with a source of supply, usually a lighting fixture, so that when 45 current is turned into the motor by manipulation of the switch in the handle of the machine, the polisher is revolved through the bevel gear transmission. When the polisher 50 is revolved, the stones carried thereby are revolved rapidly over the surface of the floor, and the latter polished or ground down to an even surface, the weight of the cast metal head, supplemented by that of the 55 vertical shaft and the weight of the stones themselves, providing sufficient pressure to carry on the grinding process. When it is necessary to move the machine to a different point, or should a high point in the floor be 60 encountered, the operator lifts the knob 41 to move the shaft 9 vertically in its bearings and through the bevel gear wheel 11, there-

by raising the polisher head from the floor. The machine may then be moved to the proper position and the polisher lowered 65 perpendicularly to again contact the surface.

By having the front of the carrier body concaved, as illustrated, the polisher may be set in close to the body and thereby not only 70 economize space, but facilitate the control of the polisher, and by mounting the handle on the carrier body by the pin and slot connection, the handle is made adjustable, so that control of the machine is facilitated; it 75 being apparent that by properly locating the handle the body may be pivoted on the rear or forward carrying wheels, to lessen or increase pressure on the polisher head.

Having thus described my invention, what 80 I claim as new therein, and desire to secure by Letters-Patent, is:

1. In a floor polishing machine, a supporting member comprising body and ground wheels, a polisher supported on said 85 body, means for actuating the polisher, and a handle having yoke arms at its lower end overlying the side edges of the body member and provided with slots; and pins on said body member projected through said 90 slots and anchoring the yoke arms to the body member.

2. In a floor polishing machine comprising a portable supporting member, having a socketed forward end, a bracket fixed to said supporting member within said socketed end, bearing members on said bracket, a shaft revolubly mounted in said bearing member, a polishing head fixed on said shaft, a bevel gear feathered on said shaft and adapted for support on said bearing member, a second shaft revolubly mounted in said bracket at right angles to said first shaft, a bevel gear fixed to said second shaft and meshing with the bevel gear on said first shaft, a motor 105 directly connected to said second shaft, a knob having pin and slot connection with the upper end of said first shaft for raising said polishing head through said socket, a latch pivotally mounted on said bearing 110 member and adapted for projection beneath said knob to hold said polishing head in elevated position, a tubular handle adjustably mounted on said supporting member, a hand grip on said handle, circuit wires in said tubular handle, and a switch in said hand grip 115 for controlling current in said circuit wires.

In testimony whereof I affix my signature in presence of two witnesses.

WILLIAM B. THAYER.
